ROTARY TAKE-UP FOR SEWING MACHINES

Arthur N. Hale, Bridgeport, Conn., assignor to
The Singer Manufacturing Company, Elizabeth, N. J., a corporation of New Jersey

Application September 3, 1942, Serial No. 457,128

16 Claims. (Cl. 112—248)

This invention relates to rotary thread take-up mechanisms for sewing machines and, more particularly, to devices for preventing abnormal winding of thread about a rotary thread take-up member.

Various expedients have been heretofore devised to minimize and in fact to prevent abnormal winding of thread about a rotary take-up member, by the provision of means for breaking or otherwise severing the thread when or after the thread begins to wind about said member. The present invention belongs in the same general category and has for its object to provide means which not only insures severing of thread winding abnormally about the take-up member, but which can also be readily assembled in thread-severing relation with respect to the take-up member.

With this and other objects in view, as will hereinafter appear, the invention consists in the devices, combinations and arrangements of parts described in connection with the accompanying drawing, which illustrates a preferred embodiment of the invention and in which:

Fig. 1 is a front end elevation of the bracket-arm head of a sewing machine containing the improved thread-severing device. Fig. 2 represents an enlarged view, partly in section, of the improved rear take-up member of a commercially well known double-disk take-up mechanism, together with the improved thread-severing member associated therewith, the section being taken on substantially the line 2—2 of Fig. 1, and in a severing-element approaching position of the take-up member. Fig. 3 is a perspective view of the improved rear take-up device, with the outer thread-confining ring indicated in dot-dash lines. Fig. 4 is a fragmentary view similar to Fig. 2, but in the position of the take-up member in which the thread-severing element extends into the peripheral groove of said take-up member substantially medianly of the length of said groove. Fig. 5 represents an enlarged perspective view of the knife-end portion of the severing element.

The present improvement has been embodied in a thread take-up mechanism corresponding in general to those disclosed in the U. S. Patents of S. Zonis, No. 2,191,736, February 27, 1940, and No. 2,263,533, November 18, 1941.

The sewing machine in part illustrated in the drawing has a frame including a bracket-arm head 10. Journaled for vertical reciprocation in the bracket-arm head 10 is a needle-bar 11, carrying at its lower end a needle 12; said needle-

bar being reciprocated by any usual or suitable actuating connections with a horizontally disposed main actuating shaft 13.

The main shaft 13 carries at one end thereof a main or front take-up disk 14 provided eccentrically of the axis of rotation of the shaft 13 with a pair of radially equidistant thread-engaging studs 15. The studs 15 carry a flat thread-confining ring 16 held spaced from the disk 14 axially of the main shaft 13. Being carried by the main shaft 13, the disk 14 and the thread-engaging studs 15 perform one rotation for each complete reciprocation of the needle 12 and in a counterclockwise direction when viewed as in Fig. 1 of the drawing.

The thread-controlling mechanism also includes a supplemental rear take-up device, including a rotary shaft 17 disposed parallel to the main-shaft 13 and actuated as described in said prior Patent No. 2,191,736, or in any other suitable or preferred manner, to perform two rotations for each rotation of and in the same direction as the main shaft 13. Carried by the supplemental shaft 17 for rotation therewith is a primary thread-confining element in the form of a disk 18, which is preferably disposed in substantially the same vertical plane as the front take-up disk 14.

Carried by the supplemental take-up disk 18 to extend laterally therefrom eccentrically of the axis of rotation of said disk is a thread-engaging member 19 rotatable in an orbital path about the axis of the shaft 17. The thread-engaging member 19, in turn, carries a secondary thread-confining element in the form of a flat ring 20 concentric with the disk 18 and held spaced laterally therefrom by the member 19; the ring 20 and the member 19 being suitably secured to the disk 18, as for example by a rivet 21. The radially spaced inner and outer circumferential faces of the thread-engaging member 19 are preferably curved substantially concentrically, with the axis of rotation of the shaft 17 as the center of curvature, as illustrated in Fig. 1 of the drawing.

At its leading end, the thread-engaging member 19 is cut away adjacent to the disk 18 to provide a convexly curved thread-deflecting side face 22 extending from the inner side face of the ring 20 across a plane medianly between and parallel to the disk 18 and ring 20, i. e., across a central plane of rotation of the member 19. The thread-deflecting face 22 of the member 19 terminates in proximity to the disk 18 in a thread-receiving throat 23.

The trailing end of the thread-engaging mem-

ber 19 is likewise cut away, but adjacent the ring 20, to provide a convexly curved thread-deflecting side face 24 extending from the side face of the disk 18 across the central plane of rotation of the member 19 to terminate in a thread-receiving throat 25 which trails the throat 23. As the leading thread-receiving throat 23 and the trailing throat 25 are disposed at opposite sides of the central plane of rotation of the member 19, the thread deflected into said throats upon abnormal winding of the thread circumferentially about the member 19 will lie across said central plane in a direction oblique to said plane, as illustrated in dot-dash lines in Fig. 2 of the drawing. It will be understood, of course, that the leading and trailing ends of the member 19 may be reversed with regard to extension thereof from the disk 18 and the ring 20.

The thread-engaging member 19 is provided in the radially outer periphery thereof with a lengthwise orbitally extending and widthwise narrow knife-receiving groove 26 disposed in substantially the central plane of rotation of the member 19, said groove 26 being preferably shallow in depth so as not to interfere with the normal handling of the thread by the member 19.

Rigidly secured upon the front end of the bracket-arm head, by screws as 27, is a face-plate 28, provided at the outer side thereof with a thickened block 29 which is cut away arcuately to extend between the front and rear rotary take-up devices in close proximity thereto. The lower portion of the block 29 is provided with a rounded aperture 30, of which the longitudinal axis is disposed in substantially the central plane of rotation of the thread-engaging member 19 and intersects the rotation axis of said member.

Secured in the block 29, by a set-screw 31 and for endwise adjustment in the aperture 30, is the cylindrical shank 32 of a knife 33 extending from one end of its shank 32. The knife 33 has symmetrically convergent blade-faces 34 meeting in a knife-edge 35 extending longitudinally of the shank 32 and disposed substantially in coincidence with the outer face of said shank, whereby said knife-edge 35 is offset from the longitudinal axis of said shank. The knife 33 also has a hollow ground rear edge 36 inclined toward the free end of the knife edge, the meeting edges of the rear and blade-faces being cut away to provide edges 37 convergent toward the free end of the knife, thereby to form a somewhat pointed free end 38. The end of the shank 32 opposite the knife is preferably provided with a transverse screw-driver slot 39 to facilitate turning of the knife to properly position the same.

In setting the knife in thread-severing position, the thread-engaging member 19 is first brought into a position in its cycle wherein it has completed giving up slack thread and is about to begin taking up thread. The exact position of the member 19 is not critical, it being merely necessary to position the member 19 oppositely to the knife 33. The knife is now turned about its longitudinal axis to align the point thereof with the groove 26, whereupon the knife is moved endwise to cause the knife-point 38 to enter said groove 26 with the knife-edge opposed to the direction of rotation of the member 19; this endwise movement of the knife being limited by the bottom of said groove 26. The convergent blade-faces 34 of the knife coat with the side walls of the groove 26 to accurately center the pointed knife in the groove 26 with

the severing edge 35 thereof disposed in a plane containing said groove. When thus positioned, the knife is secured by the set-screw 31. The knife-edge 35 is thereby disposed substantially normal to a tangent to the orbital path of the member 19 at the point of entrance of the knife into the groove 26, and the knife-shank 32 is disposed externally of said orbital path.

As illustrated in Fig. 1 of the drawing, the needle-thread *t* is normally disposed at the side of the thread-engaging member 19 opposite to the knife 33 at the time when said member is passing said knife. Consequently, the thread *t* is guarded from being accidentally severed by the knife 33 during the normal operation of the machine.

In the event of breakage of the thread during the operation of the machine, the thread may wind circumferentially about the member 19, and thereby extend over the radially outer face of the member 19 at a time when the member 19 passes the knife 33. Should this occur, the thread will be deflected by the side faces 22 and 24 of the member 19 to lie across the groove 26 of said member 19 and across the knife-edge 35, thereby resulting in severing of the thread by the knife 33. As the knife is confined at its point by the groove 26 of the member 19 at the time of severing of the thread, and as the knife-shank 32 is supported by the block 29 in close proximity to the orbit of travel of the member 19, the knife 33 is rigidly set against deflection from its proper severing position. Consequently, thread-windings about the member 19 are positively severed by the knife.

Having thus set forth the nature of the invention what I claim herein is:

1. In a sewing machine, in combination, a thread-controlling rotary take-up member provided circumferentially thereof with a knife-clearance groove and having thread-receiving throats at the opposite sides of the plane of said groove, and a stationary knife disposed to traverse said groove in the rotation of the take-up member, said knife being positioned out of range of the thread during the normal thread-controlling action of said take-up member.

2. In a sewing machine, in combination: a thread take-up device including a rotary thread-engaging member having thread-deflecting side faces inclined to the plane of rotation of said member and terminating in thread-receiving throats disposed at opposite sides of a substantially central plane of rotation of said member, whereby an abnormal winding of thread about said member will extend across said central plane, and a knife extending into the path of thread abnormally wound about said member.

3. In a sewing machine, in combination: a thread take-up device comprising a rotary thread-engaging member having leading and trailing side faces extending in opposite directions across a substantially central plane of rotation of said member, whereby an abnormal winding of thread about said member will extend across said central plane, and a knife extending into proximity to said member in substantially said plane for severing a thread wound abnormally about said member, said knife being disposed out of range of the thread during the normal thread-controlling action of said member.

4. In a sewing machine, a thread take-up device comprising, a rotary thread-engaging member circumferentially provided with a knife-clearance groove, said member having leading

and trailing side faces extending in opposite directions across the plane of said groove, whereby an abnormal winding of thread about said member will extend across said groove, and a knife positioned to traverse said groove in the path of thread abnormally wound about said member.

5. In a sewing machine, in combination, a thread take-up device including a rotary thread-engaging member rotatable in an orbital path and having thread-deflecting side faces terminating in thread-receiving throats disposed at opposite sides of a substantially central plane of rotation of said member, whereby an abnormal winding of thread about said member will extend across said central plane, said member having an orbitally extending knife-clearance groove disposed in substantially said central plane, and a thread-severing knife disposed out of range of the thread during the normal thread-controlling action of said take-up member and traversing said groove during a part of the rotation of the take-up member.

6. In a sewing machine, in combination, a thread take-up device including a rotary thread-engaging member provided with an orbitally extending knife-clearance groove, said member having leading and trailing thread-deflecting side faces extending from opposite sides of and across the plane of said groove to terminate in leading and trailing thread-receiving throats, whereby thread wound circumferentially about said member will extend at an inclination to a plane of rotation of said member and across said groove, and a stationary knife disposed out of range of the thread during the normal thread-controlling action of said take-up member and traversing said groove in each rotation of the take-up member.

7. In a thread take-up mechanism for sewing machines, in combination, a pair of substantially parallel primary and secondary thread-confining elements rotatable about a common axis, a thread-engaging member connecting said elements eccentrically of the axis of rotation thereof, said member having a thread-deflecting side face extending from the primary thread-confining element to terminate in a thread-receiving throat at the secondary-element side of said member, and said member having another thread-deflecting side face extending from said secondary element to terminate in a thread-receiving throat at the primary-element side of said member, whereby thread wound abnormally about said member will extend across the plane of rotation of said member, and a knife disposed out of range of the thread during the normal thread-controlling action of said member and extending into proximity to said member for severing thread wound abnormally about said member.

8. In a thread take-up mechanism for sewing machines, in combination, laterally spaced primary and secondary thread-confining elements rotatable about a common axis, a thread-engaging member disposed between said elements eccentrically of the axis of rotation thereof and peripherally provided between said elements with an orbitally extending knife-clearance groove, said member having a convexly curved thread-deflecting side face extending from the primary thread-confining element side of said groove to terminate in a thread-receiving throat at the secondary-element side of said groove, and said member having another convexly curved thread-deflecting side face extending from the secondary

thread-confining element side of said groove to terminate in a thread-receiving throat at the primary element side of said groove, said thread-deflecting side faces extending in opposite directions from said elements, whereby thread wound abnormally about said member will be deflected across said groove, and a thread-severing knife positioned to extend into said groove at substantially a time in the take-up rotation cycle when said member has completed giving up slack thread.

9. In a sewing machine, in combination, a thread-engaging take-up member having an orbital path of rotation and radially spaced peripheral faces about which the thread may abnormally wind circumferentially, and a stationary thread-severing member extending into the orbital path of rotation of said take-up member, said take-up member having in one of said faces a groove disposed to receive said thread-severing member and extending across an abnormal winding of thread about said take-up member.

10. In a sewing machine, in combination, a thread-engaging take-up member having an orbital path of rotation and about which member the thread may abnormally wind circumferentially, a knife-element having a thread-severing cutting edge, supporting means for said knife providing for turning movement of said knife to position said cutting edge in substantially a plane containing said orbital path of rotation of the take-up member, said supporting means additionally providing for movement of said knife toward and from said orbital path, and means for securing said knife in set position to sever an abnormal winding of thread about the take-up member in the rotation of said member.

11. In a sewing machine, in combination, a thread-engaging take-up member having an orbital path of rotation and about which member the thread may abnormally wind circumferentially, said member being provided with an orbitally extending knife-clearance groove across which the abnormal winding of thread will extend, a knife-element having a cylindrical shank and having a thread-severing cutting edge offset from the longitudinal axis of said shank, supporting means for the shank of said knife-element providing for turning and endwise movement of said knife-element, and means for securing said knife with the cutting edge thereof disposed in the orbital plane of and extending into said groove.

12. In a sewing machine, in combination, a thread-engaging take-up member having an orbital path of rotation and about which member the thread may abnormally wind circumferentially, said member being provided with an orbitally extending knife-clearance groove across which the abnormal winding of thread will extend, a knife-element having a cylindrical shank and having blade-faces symmetrically converging in a cutting-edge, supporting means for said knife providing for endwise movement of the knife toward the orbital path of said take-up member, said supporting means additionally providing for turning movement of said knife to center the cutting-edge thereof in said groove, and means for securing said knife in set position.

13. A thread-severing knife for rotary take-ups of sewing machines, comprising a cylindrical shank provided at one end thereof with blade-faces converging in a cutting-edge disposed substantially in coincidence with the outer face of said shank, said knife having the back face

thereof opposite said cutting edge hollow ground and inclined toward the free end of said cutting edge; and the meeting edges of said blade and back face being cut away to converge substantially at the free end of said cutting edge, whereby the knife has a pointed free end.

14. A thread-controlling take-up unit for use in connection with sewing machines, comprising, laterally spaced and substantially parallel primary and secondary thread-confining elements, 10 and a thread-engaging member connecting said elements and having thread-deflecting side faces extending in opposite directions across a plane parallel to and between said elements; said side faces of the thread-engaging member terminating in thread-receiving throats disposed respectively at opposite sides of said plane.

15. A thread-controlling take-up unit for use in connection with sewing machines, comprising, laterally spaced primary and secondary thread-confining elements, and a thread-engaging mem- 20

ber connecting said elements and peripherally provided with a groove lengthwise disposed in a plane centrally between said elements; said member having oppositely directed thread-deflecting side faces terminating in thread-receiving throats disposed respectively at opposite sides of said plane.

16. A thread-controlling take-up unit for use in connection with sewing machines, comprising, a disk, a member extending from a side face of said disk eccentrically of the center of said disk, a substantially flat ring carried by said member in spaced relation to and concentrically with said disk; said member being provided in its outer face between said disk and ring with a groove extending circumferentially of said member, and said member being provided at opposite sides of said groove with thread-receiving throats opening in opposite directions.

ARTHUR N. HALE.
